FIRE HOSE NOZZLE

Duncan Horatio Campbell, Borough of Etobicoke, Ontario, Canada, assignor to Wilson & Cousins Co. Limited, Toronto, Ontario, Canada, a company of Canada

Filed Oct. 2, 1968, Ser. No. 13,823

Term of patent 14 years

Int. Cl. D23—01

U.S. Cl. D23—34

FIG. 1

FIG. 2

FIG. 3

FIGURE 1 is a perspective view of a fire hose nozzle showing my new design;

FIGURE 2 is a side elevational view thereof; and

FIGURE 3 is a perspective view of the base portion as shown in FIGURES 1 and 2.

The dominant features of my design reside in the portions shown in full lines.

I claim:

The ornamental design for a fire hose nozzle, as shown and described.
